UNITED STATES PATENT OFFICE.

JOHN E. PRUNTY, OF BALTIMORE, MARYLAND.

RELIEF-VALVE FOR STEAM FIRE-ENGINES.

SPECIFICATION forming part of Letters Patent No. 311,145, dated January 20, 1885.

Application filed July 2, 1874.

To all whom it may concern:

Be it known that I, JOHN E. PRUNTY, of the city of Baltimore, in the State of Maryland, have invented certain Improvements in 5 Automatic Relief-Valves for Attachment to Steam Fire-Engines, or for general purposes, of which the following is a specification; and I do hereby declare that in the same is contained a full, clear, and exact description there- 10 of, reference being made to the accompanying drawings, and to the letters of reference marked thereon.

My present invention relates to certain improvements upon the inventions set forth in 15 my Letters Patent Nos. 122,059 and 126,330; and for the better understanding hereof reference is directed to said Letters Patent.

The purpose of all my said several inventions is to furnish means whereby a back cur- 20 rent in the hose or pipes, caused by any ob- struction in the hose, &c., is carried off safely without subjecting the machinery to sudden shocks, and the hose or pipes to a pressure likely to burst them. In Letters Patent No. 25 122,059 the result is obtained by means of balanced double puppet - valves suitably ar- ranged in a valve - chamber communicating with the body of the valve and the eduction or relief pipe, said valves being adapted to 30 be held to their seats by a set-screw, when re- quired. In Patent No. 126,330 an addition is shown of a swinging device, termed in that 35 patent a "concentric ring," to aid the valves in keeping their seats when the said valves are closed by the action of the current.

In my present invention the several fea- 40 tures substantially as set forth in Patents Nos. 122,059 and 126,330 are employed.

The invention herein described is an expe- 45 dient to be used at the option of the engineer in charge, (supposing the relief-valve to be at- tached to a steam fire-engine,) in view of cer- tain conditions under which the engine may be placed, wherein the supply of water for the 50 engine does not flow under pressure, but must be lifted or drawn to and by the engine. By referring to Letters Patent No. 122,059 it will be seen that the set-screw E operates di- rectly upon the double puppet-valves to hold 55 them to their seats when water is to be thus supplied to the engine. This seating of the

valves is necessary when the engine starts, since the air in the suction-chamber must be driven up into the air-vessel, to the side of which my relief-valve is attached, for were 55 the double puppet-valves not thus held to their seats a circulation of air would be main- tained through the chambers of the valve and a vacuum in the suction-chamber never ob- tained, preventing thus the flow of water to 60 the engine. The said set-screw E shown in my Patent No. 122,059 serves effectually for this purpose under the ordinary and almost all the conditions wherein my relief-valve has been used; but under certain extraordinary 65 circumstances it has been found necessary, or at least advisable, to exert a variable pressure upon the valves, and at other times to relieve them from all pressure. With a view to meet- 70 ing these emergencies I use an adjustable spring to operate upon the double puppet- valves, which spring is arranged so that it will exert the desired variable pressure, or can be removed, at the will of the engineer, en- tirely from contact with the puppet-valves. 75

While it is unnecessary to explain all the 80 advantages which attend the use of an adjust- able spring with the puppet-valves, it may be stated that however compressed, the spring would still admit of a slight motion of the 85 valves upon a reverse current of the water taking place, and prevent the bursting of the hose, and that the adjustable spring, besides having this merit, which a screw does not pos- sess, can be as easily drawn entirely from con- 90 tact with the valves, where they are to be left free from any such contact. On the other hand, should the engineer forget to withdraw the screw from touching the valves and a re- 95 verse action of the water occur, the bursting of the hose would follow.

In the further description of my invention 100 which follows, due reference must be had to the accompanying drawings, in which—

Figure 1 is a longitudinal section of my im- 95 proved relief-valve, as set forth in my Letters Patent Nos. 122,059 and 126,330, and embody- ing, also, the improvements herein claimed. Fig. 2 is a view of a detached portion of my invention.

Similar letters of reference indicate similar parts of the invention in both views.

In place of the set-screw E and its cap shown in Patent No. 122,059, the devices described as follows are used: The cap A is screwed into its end of the valve-chamber B, 5 as shown, and is recessed, forming a seat for a spring, a, coiled around the stem b. The stem b is provided with two collars or flanges, one of which, c, is screwed into the end thereof, and designed to fit against the end of the 10 valve-stem. The other collar, d, is a part of the stem b, and fits, when the spring is distended, against the end of the recess in the cap A. The front end of the recess in the cap is occupied by the screw-plug C, through 15 which the stem passes, fitting neatly therein. The outer end of the screw-plug is inclined, and serves as a means for holding the stem b out, when withdrawn, by means of the small milled handle d', a pin, e, being placed in 20 the stem b, which pin is caused, when the handle is pulled out, to bear upon that part of the inclined face of the plug projecting most, the stem being twisted or turned around. A small indentation is made in the face of the 25 plug C, to receive the pin at the point of the greatest projection reached by the pin. By the means shown the stem b is drawn from contact with the double puppet-valves, allowing them a free movement. The stem b, when 30 touching the valve-stem, exerts a variable pressure upon the valves, which cannot be obtained by means of a set-screw, as shown by E in Letters Patent No. 122,059.

D is the aforementioned swinging device, the office of which is hereinbefore referred to, 35 and more particularly described in my Letters Patent No. 126,330.

In the present invention the eduction or relief pipe F is connected to the suction-chamber of the pump, so that the backwater can 40 be drawn off and recirculated without jarring or straining the parts.

I am aware that puppet-valves or valves of other descriptions have had springs applied to them for various purposes, and to claim 45 such is not my intention, it being my purpose to claim only the spring in the relation herein shown.

I disclaim so much of the device herein illustrated and described as is claimed in an application filed by me March 25, 1884, Serial No. 125,428, which application is a division of the present one.

I therefore do claim as my invention—

The combination, in a relief-valve, of a 50 spring with double puppet-valves, suction and relief pipe, and vibrating ring, said spring being adjusted to prevent air passing the valves until water has been obtained, substantially as set forth.

In testimony whereof I have hereto subscribed my name this 25th day of June, 1874.

JOHN E. PRUNTY.
